EDUARD EGLI, OF RUTI, SWITZERLAND, ASSIGNOR TO MASCHINENFABRIK RÜTI
VORMALS CASPAR HONEGGER, OF RUTI, ZURICH, SWITZERLAND.

LOOM FRAME AND SLAY.

Application filed January 18, 1927, Serial No. 161,921, and in Switzerland April 13, 1926.

The loom frames and slays hitherto known have been constructed either for overpick or for underpick, for loose reed or for fast reed, for single-shuttle or for multiple-shuttle working, for light or for heavy fabrics, for non-automatic or for automatic working, without it being possible, on one and the same loom, to carry out at will all the kinds of work mentioned. Consequently for each kind of work special main frames, a special breast beam and a special slay are required, which considerably increases the cost of manufacture.

Now the present invention relates to a loom frame and slay which enables all the above-mentioned kinds of work to be carried out and may consequently be designated a unitary loom frame and slay, and as such renders possible a considerable simplification and cheapening of the manufacture.

This result is obtained according to the invention owing to the fact that each of the two main frames has cut surfaces for the arrangement of the loom frame as an overpick or as an underpick loom frame, as a loose reed or as a fixed reed loom frame, as a single-shuttle or as a multiple-shuttle loom frame, for light or heavy fabrics of any desired material, as a frame for a non-automatic or as an automatic loom for pick and pick goods or terry weaving, and also has supporting apertures bored by means of templates for the reception of fitted bearing hubs for the crank shaft, the lower loom shaft, and the rocking shaft for the batten. The invention is further characterized by the fact that the frame cross-bars are connected with the main frames in the planes of the inner cut surfaces, that the breast beam is constructed for the reception of a loose reed and of an automatic weft replenishment, and that the slay consists of three main parts, which are constructed for the optional use of the slay as a loose or fast reed slay, as an over or as an underpicker slay, as a single-shuttle or a multiple-shuttle slay, as an automatic or non-automatic pick and pick or Turkish towelling slay.

The accompanying drawings illustrate one constructional example of the invention;

Figs. 1 and 2 are an elevation and a plan respectively of one main shield or frame of the loom;

Fig. 3 is a section on a larger scale on the line $x-x$ in Fig. 1, and of one crank shaft bearing;

Fig. 4 shows a part of one main shield in end elevation and a part of one front cross-bar connected therewith.

Figs. 5 and 6 are an elevation and a plan respectively of the breast beam,

Figure 7 is a cross section of the breast beam, when used for loose reed, taken on the line I—I in Figure 6,

Figure 8 is a cross section of the breast beam, when used for fixed reed, taken on the line II—II in Figure 6,

Figure 9 is a cross section of the breast beam, when used for automatic weft replenishment, taken on the line III—III in Figure 6,

Figs. 10 and 11 are an elevation and a plan respectively of the slay.

Figure 12 is a cross section of the slay, when used as a loose reed slay, taken on the line IV—IV in Figure 11,

Figure 13 is a cross section of the slay, when used as a loose reed slay with adjustable resilient shuttle back, taken on the line V—V in Figure 11,

Figure 14 is a cross section of the slay, when used as a fixed reed slay with adjustable shuttle back, taken on the line VI—VI in Figure 11.

In the case of the main frame A (Figs. 1 to 4) 1 and 2 denote cut surfaces on its outer sides for the reception of picking shaft bearings for the arrangement of the loom as an overpick or underpick loom. 3, likewise on the outer side of the main frame A, denotes cut surfaces for the reception of buffer supports for the fixed reed devices for the arrangement of the loom as a fixed reed loom.

4, on the same side of the main frame A, denotes cut surfaces for the reception of auxiliary supports for the stiffening of the crank shaft for the loom drive for the employment of the loom for high speeds of revolution, heavy fabrics of rather large overall widths of loom. 5 (Fig. 1), on the same side of the main frame A, denotes cut surfaces for the reception of a device for letting off or delivering the warp, for the arrangement of the loom as an automatic loom or as a non-automatic loom.

6, on the same side of the loom denotes cut surfaces for the reception of a box motion for the arrangement of the loom as a multiple-box or check loom and as a pick and pick loom. 7 and 8 are two holes bored in the lower part of the main frame A for the reception of the rocking shaft for the

110

lay when employing the loom for light and heavy fabrics. 9 and 10 are supporting apertures in the main frame A for the reception of a bearing bush 11 (Fig. 3) for the 5 crank shaft 12 and a bearing bush 11 of the same construction for the lower shaft 13. The holes 7 to 10 are bored by means of a template, whereby an exceedingly accurate supporting of the shafts is obtained, the distance between the axes of the shafts being 10 constant for all frames. Each bearing bush 11 has flanges 11' for securing the bush to the frame by means of screws. These screws are only intended to hold the bush firmly in 15 an axial direction, while they are relieved of any stress in a shearing direction in consequence of the fitting of the bearing bush into the hole bored in the frame.

The same bearing bush 11 may be employed 20 either in a vertical or in a horizontal position, and all parts are exchangeable.

On the inner side of each loom frame A, cut surfaces 14 (Figure 4) receive the stop surfaces 15 of the front and rear cross-bars 16.

The breast beam 17 (Figures 5 to 9) belonging to the unitary loom, is constructed so as to be used for fixed reed, as shown in Figure 8, or for loose reed, as shown in Figure 7, or for automatic weft replenishment as shown in Figure 9. In this connection, Figure 7 shows the fastening of the adjustable angle for the arresting of the throw of the reed for loose reed 7', whilst Figure 8 shows 35 the fabric-carrying ledge 8' and the spreading roller 8² for the fast reed loom, and Figure 9, the cut surface 9' for the single-shuttle and multiple-shuttle automatic weft replenishment.

40 If in a weaving loom having a loose reed, the shuttle stops short in the shed, the slay nevertheless advances in the front position, as it is known, but the reed is thrown back-

wards, the loom is stopped and no tearing of the threads takes place.

The slay 30 (Figures 10 to 14), belonging to the unitary loom frame and slay, consists of three main parts B, C and D and, as shown in Figures 12, 13 and 14, is designed for optional use as a loose reed or a fast reed slay, as an overpick or an underpick slay, as a single shuttle or a multiple-shuttle slay, and as an automatic or a non-automatic pick and pick or Turkish toweling slay.

What I claim is:

A unitary loom frame and slay, comprising two main frames, each formed with cut surfaces adapted to enable the arrangement of the loom frame as an overpick and as an underpick loom frame, both as a loose and as a fixed reed loom frame, both as a single-shuttle and as a multiple-shuttle loom frame, both for light and for heavy fabrics of any material, and both as an automatic and as a non-automatic loom for pick and pick goods and terry weaving, said main shields each being also formed with bearing apertures bored by means of templates for the reception of bearing hubs for the crank shaft, the lower loom shaft and the rocking shaft, the loom frame further comprising cross-bars connected with the main frames in the planes of the inner cut surfaces, a breast beam constructed for the reception of a loose reed and of an automatic weft replenishment, and a slay 70 consisting of three main parts adapted to enable the slay to be used both as a loose reed slay and as a fixed reed slay, both as an overpick slay and as an underpick slay, both as a single-shuttle slay and as a multiple-shuttle slay, and both as an automatic and as a non-automatic pick and pick and Turkish toweling slay.

In testimony whereof I have affixed my signature.

EDUARD EGLI.
